SYDNEY L. DIGNON AND MICHAEL L. DEBROSEE, JR., OF NEW YORK, N. Y.

NON-REFILLABLE BOTTLE.

1,072,583.

Specification of Letters Patent.

Patented Sept. 9, 1913.

Application filed December 14, 1912. Serial No. 736,671.

To all whom it may concern:

Be it known that we, SYDNEY L. DIGNON and MICHAEL L. DEBROSEE, JR., citizens of the United States of America, residing at 5 426 East One Hundred and Fifty-fifth street and 3107 Park avenue, New York, N. Y., United States of America, have invented new and useful Improvements in Non-Refillable Bottles, of which the following is a 10 specification.

This invention relates to non-refillable bottles and has for its objects a device of this character which will be simple and effective in operation, which is not liable to get out 15 of order, and which will be inexpensive to manufacture. Other objects will in part be obvious and in part be pointed out hereinafter.

An illustrative embodiment of the invention 20 is shown in the accompanying drawing, which represents a vertical sectional view of the neck of a bottle having the improved device positioned therein.

Referring to the drawing, 1 represents a 25 bottle having a neck 2 provided with an inwardly extending shoulder 3 adjacent the lower end thereof, and with a groove or grooves 4 intermediate the shoulder 3 and the upper end of the neck. The distance 30 between the shoulder 3 and the groove or grooves 4 is substantially equal to the height of the non-refillable device.

The device for preventing the refilling of the bottle is positioned in the neck thereof, 35 and comprises a shell 5 formed of any suitable material, as for example, hard rubber, or the like, which shell is cylindrical in form and of a diameter such that it will fit snugly within the neck of the bottle. The 40 lower end of the shell is provided with a port or opening 6 and its upper end is provided with an interior thread 7. When in position within the neck of the bottle, the lower end of the shell rests upon the 45 shoulder 3, whereby it is prevented from downward movement with respect to the bottle.

The upper end of the shell 5 is closed by a plug 8, preferably formed of the same material 50 of which the shell is formed, and provided with threads adapted to engage the threads 7 formed in the shell. The plug is provided with a depending portion 9, which extends within the shell, being reduced in 55 size, as clearly shown in the drawing, whereby a passageway is formed between it and

the inner wall of the shell 5. The plug is provided with an opening 10 in its upper portion which communicates, through laterally extending openings 11, with the above 60 mentioned passageway.

A washer 12, formed of rubber or the like, is positioned between the plug 8 and the shell 5, and its width is such that its outer edge projects beyond the outer edge of the plug 65 so that as the assembled device is forced into the neck of the bottle, after the same has been filled, the edge of the washer will be forced to occupy a position between the edge of the upper end of the plug and the neck of 70 the bottle.

The groove or grooves 4 are so positioned that when the device is in position the washer 12 will extend across the groove or grooves 4, and owing to the resiliency of the material 75 of which the washer is made, a portion thereof will be forced into the groove, as clearly shown in the figure, thereby locking the device securely in position and preventing its withdrawal from the neck of the bottle. 80

The depending portion 9 of the plug 8 has formed therein an upwardly extending recess 13, within which the upper portion of a valve member 14 extends. This valve member is preferably formed of glass or the 85 like, and is provided at its lower end with a portion adapted when in its normal position to close the port 6 in the shell 5. The valve member 14 is normally held in its closed position by gravity and by means 90 of a spring 15 positioned within the recess 13 and engaging the inner wall of the recess and the upper end of the valve member. The tension of this spring is such that it will slightly overcome the weight of the 95 valve member 14, so that if the bottle be inverted, when empty, the valve member 14 will be held upon its seat. As the spring, however, just overbalances the weight of the valve member 14, it follows that if there 100 is any appreciable amount of liquid in the bottle the weight of the liquid in addition to the weight of the valve member will be sufficient to overcome the spring and to force the valve member off its seat, thus permitting the liquid to flow out of the bottle. 105

In order to assist in guiding the movement of valve member 14 it is preferably provided with an upwardly extending pin 16, the free end of which extends within a 110 recess 17 formed in the depending portion 9 of the plug. This recess is of such a length

as to allow the opening of the valve member 14.

The operation of the device which should be largely apparent from the drawing is as follows: Assuming the bottle to be filled with liquid, if it is desired to pour the liquid therefrom it is merely necessary to tilt the bottle in the usual manner and owing to the weight of the liquid the valve member 14 will be forced from its seat thereby permitting the liquid to flow through the port 6, through the passageway between the shell 5 and the depending portion 9 of the plug 8, and then through openings 11 and 10 and out of the bottle. When the bottle is returned to its normal position the weight of the valve member 14 and the pressure of the spring 15 will force the valve member upon its seat effectively sealing the bottle. After the bottle has been emptied it will be impossible to refill it for the spring 15 will, as above described, hold the valve member 14 against its seat even when the bottle is inverted, and there is, therefore, no way by which the valve member 14 can be moved from its seat. The device as a whole cannot be removed from the neck of the bottle, nor can the plug be unscrewed from the shell by reason of the fact that the washer 12 extends within and interlocks with the groove or grooves 4. If it be attempted forcibly to withdraw the device, as for example, by inserting a wire through the openings 10 and 11, the result would be the breakage of the parts, which as above described, are formed of hard rubber or the like, which is brittle and not adapted to stand the pulling strain which would be necessary to overcome the locking action of the washer 12 and groove 4.

Having described this invention, in connection with the illustrative embodiment thereof, to the details of which disclosure the invention is not, of course, to be limited, what is claimed as new and what is desired to be secured by Letters Patent is set forth in the appended claim:

In combination, a bottle provided with a shoulder in its neck portion adjacent the lower end thereof and with a groove intermediate its ends, a shell fitting within the neck of the bottle and resting on said shoulder, said shell having an opening in its lower end, the upper end of said shell being open and being provided with an interior thread, a plug provided with threads engaging the threads in said shell and with a flange adapted to register with the upper edge of the wall of said shell, a washer interposed between said upper edge of the shell and said flange and provided with a portion overlying the outer surface of said flange whereby it will be interposed between said flange and the neck of the bottle, said overlying portion of said washer extending into said groove to lock said plug and said casing against movement, said plug being provided with an opening communicating with the interior of said shell, and a valve member within said shell coöperating with the opening in the lower end thereof to open and close the same.

In testimony whereof we have signed our names to this specification in the presence of two subscribing witnesses.

SYDNEY L. DIGNON.

MICHAEL L. DEBROSEE, JR.
